UNITED STATES PATENT OFFICE.

ALFRED A. SCHRATZ, OF DETROIT, MICHIGAN.

FLUID-MIXING FIXTURE.

SPECIFICATION forming part of Letters Patent No. 659,260, dated October 9, 1900.

Application filed May 3, 1900. Serial No. 15,324. (No model.)

To all whom it may concern:

Be it known that I, ALFRED A. SCHRATZ, a citizen of the United States, residing at Detroit, county of Wayne, State of Michigan, have invented a certain new and useful Improvement in Fluid-Mixing Fixtures; and I declare the following to be a full, clear, and exact description of the same, such as will enable others skilled in the art to which it pertains to make and use the same, reference being had to the accompanying drawings, which form a part of this specification.

This invention relates to a fixture for mixing a disinfecting fluid with water, and has for its object an improved fixture intended to be used in places where it is desired to employ an antiseptic wash-water; and the purpose of the invention is to produce a fixture which will mingle an antiseptic fluid with a stream of water flowing from any source of supply.

In the drawings, Figure 1 is a vertical elevation, partly in section. Fig. 2 is a drawing, mostly in section, and shows the parts as they appear on a plane passing diametrically and vertically through the fixture and at right angles to the plane of the section shown in Fig. 1.

1 indicates the stem, which is arranged to be secured to a table-top by a spindle 1^a, screw-threaded at its end, adapted to be passed through the table-top and to have a nut 1^b run onto the threaded part of the spindle. The fixture is provided with a chamber 2, into which lead water-pipes 2^a and 2^b, one of the inner leading water-pipes being intended for warm water and the other for cold water, each leading from an independent source of supply, as from a water-main and a boiler. Each water-main is provided with its individual cut-off valve 2^c and 2^d. From the bottom of the chamber a passage 2^e leads out to a faucet 2^f. From the upper end of the chamber 2 a passage 2^g leads upward to a valve 3. Between the outlet 2^g and the valve 3 there is a check-valve 3^a, seating downward and adapted to be opened by the flow of liquid from the chamber 2. Above the check-valve 3^a is an adjusting-nozzle 3^b, which limits the opening movement of the check-valve and which may be adjusted by changing its vertical position with reference to the check-valve. The ad-

justment is effected by making the nozzle as a screw-nipple and engaging it in the hollow screw 3^c, which forms the upper part of the fixture just below the casing of the valve 3. 55 A valve-casing 4 is located just above the parts previously described and is fitted with a three-way plug-valve 3. The passage leading from the chamber 2 leads into the chamber of the valve-casing 4, and a second passage 4^a leads vertically downward into the same chamber from a higher part of the fixture. On the upper end of the fixture is mounted a tank 5, the outlet of which is engaged in the fixture and the passage through the outlet of which communicates with the passage 4^a, and through the passage 4^a it communicates with a passage 3^d in the plug-valve. In the passage 4^a, between the tank and the upper portion of the casing 4, is inserted a pressure-reducing nipple 6, which is removable from the fixture. The nipple 6 is provided with a flange 6^a, that rests on an annular shoulder 4^b in the fixture. The nipple is provided with a hollow stem-like projection 75 perforated with small holes 6^b, which constitute communicating passages through the nipples between the tank and the casting, and a nipple with holes of proper size with reference to the head of the water and with 80 reference to the size of the tank 5 may always be used—as, for example, if the tank 5 be large, so that there will be a considerable head of liquid in it, a nipple with small perforations 6^b may be selected and the outflow of liquid limited, and this limitation may be made with reference to the normal flow of water through the pipes 2^a and 2^b. Such regulation need only be made once for the same instrument, and it is consequently not necessary to make this part adjustable, as the single adjustment of the nozzle 3^b will suffice to regulate with sufficient accuracy the mingling of the water with the antiseptic. The plug-valve 3 is turned by a handle 7 to bring 95 the passage 3^e and the passage 3^d into position to permit the flow of water from the passage 2^g through the passage 3^e to the outflow-nozzle 8 and at the same time to permit the flow of the antiseptic liquid through the passage 3^d into the passage 3^e. When thus arranged, the mingling water and antiseptic

are delivered from the nozzle 8. Clear water may be drawn from the nozzle 2^f. Generally when clear water is drawn the valve 3 is turned to prevent the passage through it of either water or antiseptic; but even if it be not turned the check-valve 3^a prevents the return flow of water through the passage 2^h and prevents the entrance of any antiseptic into the chamber 2.

10 What I claim is—

1. In a fixture for mingling antiseptic fluid with water, in combination with a standard provided with an inflow-pipe for water and a nozzle for the delivery of the same, an antiseptic-tank connected with the fixture, a three-way valve adapted to allow the flow therethrough of both water and the antiseptic liquid, a nozzle for the delivery of the mingled liquids, and a check-valve in the fixture 15 between the inflow-pipe for water and the

three-way valve, and also between said two delivery-nozzles, substantially as described.

2. In a fixture for mingling antiseptic fluid with water, in combination with a standard provided with an inflow-pipe for water, an 25 antiseptic-tank connected with the fixture, a three-way valve adapted to allow the flow therethrough of both water and the antiseptic liquid, a check-valve in the fixture between the inflow-pipe for water, and the three-way 30 valve, and a regulating-nipple adjustable with respect to the check-valve, and adapted to determine the amount to which the check-valve opens, substantially as described.

In testimony whereof I sign this specification in the presence of two witnesses.

ALFRED A. SCHRATZ.
